UNITED STATES PATENT OFFICE.

WALTER L. FAIRCHILD, OF NEW YORK, N. Y.

PROCESS OF FORMING PNEUMATIC TUBES.

Application filed September 2, 1925. Serial No. 54,053.

This invention relates to a new and improved method of producing hollow rubber articles, such as pneumatic tubes for vehicle tires and the like.

5 One of the objects of the invention is to provide a new and improved method of producing a pneumatic tube wherein the cost of production is reduced to a minimum.

Another object of the invention is to provide 10 a new and improved process of vulcanizing a raw rubber tube, wherein there is produced a tube without seams, and a tube wherein all the material of the tube is thoroughly vulcanized.

15 A further object of the invention is to provide a new and improved method of the above character, which may be carried on more expeditiously than it has been possible to carry on vulcanizing operations on 20 pneumatic tubes and the like according to practices hitherto pursued.

Other objects and aims of the invention more or less specific than those referred to above, will be in part obvious and in part 25 pointed out in the course of the following description of the steps and the relation of each step to one or more of the others there- of employed in carrying out my process, and the scope of protection contemplated 30 will be indicated in the appended claims.

In the accompanying drawings wherein I have shown schematically a preferred embodiment of my improved method adapted for use in producing pneumatic tubes:

35 Figure 1 is a plan view of a tube of raw rubber, which is of suitable length to be formed into a pneumatic tube.

Figure 2 is a similar view of the tube, showing the ends united, with the valve 40 stem inserted in place.

Figure 3 is a sectional view showing a preferred form of apparatus adapted for use in carrying out my improved process, also showing the pneumatic tube mounted 45 in the mold, when the first step of my improved method has been carried on in connection with said tube.

Figure 4 is a sectional view through a portion of the mold, showing the tube 50 mounted therein when the second step of my improved method has been performed.

Figure 5 is a sectional view showing the valve illustrated in Figure 3, in a different position.

55 Figure 6 is a view of said valve in the position shown in Figure 1, to which posi-

tion it has been moved after the operation shown in Figure 4 has been carried out.

Figure 7 is a sectional view similar to Figure 4, showing the tube in the closed 60 mold, after a third step of the operation of my improved method has been carried out.

Figure 8 is a view of the valve shown in Figures 3, 5 and 6, in the position to which it has been moved to carry out the step of 65 the operation illustrated in Figure 7.

Figure 9 is a view similar to Figure 7, showing the tube in the closed mold after the fourth step of my improved method has been carried out.

70 Figure 10 is a view of the valve shown in the preceding figures, in the position it has been moved to carry out the step of my method illustrated in Figure 9.

Figure 11 is a view of said valve showing 75 the position of the valve illustrated in the preceding figure, in the position it is moved immediately subsequent to the carrying out of the step of the method illustrated in Figure 9.

Figure 12 shows the tube mounted in the molding apparatus, where it is being subjected to the fifth step of my improved method; and

Figure 13 shows the tube in the mold after 80 vulcanization, and after the concluding step of my improved method has been carried on with respect to said tube.

Referring now to the drawings, wherein 85 similar reference characters refer to similar parts throughout the several views, the reference numeral 1 indicates a tube of raw rubber, which has been produced in any suitable way, as for instance, by means of a tubing machine, and which has been cut 90 to a suitable length to produce a tube of the desired diameter. The ends of this tube of raw rubber are then brought together and united in any suitable way to produce the tube 2, a valve stem 3 having been inserted 95 in the tube before the ends thereof were united. The manner of inserting the valve stem and splicing the ends of the tube together form no part of the present invention, although I prefer to utilize the method 100 disclosed in my co-pending application Serial Number 11,006, filed February 24th, 1925.

105 The reference numeral 4 denotes one section of a circular mold, having one part of 110 the molding chamber illustrated at 5, said mold being preferably steam jacketed, the

steam chamber being indicated at 6. The section 4 has a laterally extending arm 7, to which is pivoted at 8 the upper section 9 of the mold, having the complementary part 10 of the mold or vulcanizing chamber. This section of the mold is also steam jacketed, the stem chamber being illustrated at 11.

When the mold sections 9 and 10 are brought together in mating relation a circular closed compartment or vulcanizing chamber is formed between the mating sections, as illustrated in Figures 12 and 13. It will be understood that the meeting faces 15 of the mold sections are so ground and fitted together that they will have a substantially perfect fit, whereby no part of the tube to be subjected to the vulcanizing process will be forced between the meeting edges of the 20 sections of the mold.

At this point it may be noted that I prefer to form the mold sections so that the greater part of the vulcanizing surfaces of the mold will be located in the lowermost mold section, as illustrated in my pending application, Serial Number 521,391, filed December 10th, 1921. In other words, the mold is divided above its centre for a reason which will be apparent hereinafter. It will also be noted 25 that the vulcanizing chamber of the mold is given an oval cross-section, so that the finished tube will have a like cross-sectional contour when the vulcanizing operation has been performed thereon.

30 The above described assembly of mold sections is pivotally mounted at 12 upon a suitable supporting standard 13, so that said assembly may be swung to the various positions hereinafter to be described.

40 The reference numeral 14 illustrates a valve casing of a three-way valve 15, which may be operated as by means of the handle 16. Communicating with the valve chamber 14 is a conduit 17 which leads from a 45 suitable source of exhaust, not shown, such for instance as a vacuum tank. Leading also into this valve casing 14 is a conduit 18 which extends from a source of fluid pressure, not shown, for instance, a tank filled 50 with air, carbon dioxide, or other gas under pressure.

55 Leading from the valve casing 14 is a conduit 19 which extends through a valve casing 20, suitably mounted upon a vulcanizing apparatus. A V-shaped passageway 21 in the valve member 14 is adapted to connect either the vacuum conduit 17 with the conduit 19, or the fluid pressure conduit 18 with said conduit 19, the valve member 15 when 60 moved to the position shown in Figure 3, being operative to shut off communication from both the vacuum conduit and the fluid pressure conduit from the conduit 19. Leading from the valve casing 20 is a conduit 22, preferably flexible, which extends

through the valve stem 3 of the tube 2 positioned in the chamber 5 of the mold section 4.

Leading into the valve casing 20 is a conduit 23 which extends from a source of a heated fluid medium under pressure, which is suitable to be employed as a vulcanizing gas. In the present instance I have indicated the conduit 23 as leading from a source of steam pressure not shown. Located in 75 the valve chamber 20 is a valve 24 having the V-shaped passageway 25. This valve member 24 may be so moved as to connect either the conduit 19 with the conduit 22, or the conduit 23 with the conduit 22, or to 80 such a position as will shut off both conduits 19 and 23 from the conduit 22. In the present instance the valve 24 is provided with a laterally extending arm 26 adapted to be operated by means of a link 27 extending 85 from the tiltable platform 28, upon which the lower section 4 of the mold is mounted, so that when the mold assembly is swung upon its pivotal axis 12 the valve 24 will be operated in a manner hereinafter to be 90 described.

95 It will be understood, of course, that the mechanism illustrated in the drawing, employed for carrying out the various steps of my process is largely schematic, the preferred form of mechanism being illustrated in my application Serial Number 54,054, filed contemporaneously herewith.

Also it will be understood that in practice means will be employed for locking the 100 mold sections together and for supplying steam to the steam chambers 6 and 11 of the mold sections.

Referring now to the first step of my method, subsequent to the formation of the 105 tube 2, and the insertion of the valve stem 3, the latter is connected with a suitable source of vacuum to collapse the tube. This operation may be preferably performed prior to depositing it in the lowermost section 4, as illustrated in Figure 3. The conduit 22 is then connected with the valve stem 3, the collapsed tube occupying a position substantially as shown in Figure 3 of the 110 drawings.

115 The valve 15 is then operated to connect the conduits 18 and 19, sufficient air being projected into the tube 2, resting in the valve chamber 5, to partially inflate the same, causing the outer wall of the raw rubber tube 120 to engage with the heating surface of the lower mold section 4. At this point it may be noted that air, or other gas, forced in the tube of raw rubber, during this step of my mold, is relatively cool, so as to counteract the effect of the heated mold 4, and to prevent the raw rubber tube from collapsing within the heated section; and also to prevent the upper edge of the tube 2 from lopping over on the edge of the mold section, 125 130

whereby it would be pinched in between the mating edges of the mold section when they are closed. The cold gas further retards the vulcanization of the tube for a short time, thus preventing the compound of raw rubber to be softened before the hardening process of vulcanization takes place. Only sufficient air is projected into the tube during this operation, to cause the same to take 10 on a form substantially shown in Figure 4 of the drawings. The upper section 9 of the mold is then closed down on the lower section, whereupon the valve member 15, which was moved to a neutral position after the insertion of the initial air into the tube, is again moved to connect the tube with a source of air to expand it within the heated mold, so that its outer wall will effect a close engagement with the vulcanizing surface of 15 the mold chamber. When this step of the method has been accomplished, the valve member 15 is then again operated to connect the inflated tube within the mold chamber with a source of vacuum through conduit 20 25 17, so that all air pressure within the tube will be removed. It is not intended, however, that sufficient suction will be applied to the tube to cause it to become disengaged with the heating surface of the mold chamber.

With reference to Figure 3 it will be seen that when the mold section 4 is in a horizontal position, the valve member 24 has a partly open connection between the conduit 19 and 30 the conduit 22, the operations above described having been accomplished by manipulating the valve member 15 by its handle 16.

Having reduced the air pressure within 40 the tube to sub-atmospheric pressure, the suction is then shut off and steam under pressure is forced therein. A convenient way of performing this step of the method is exemplified in the mechanism shown in the drawings, which step is accomplished by 45 tilting the mold assembly upon its pivotal support 12 to the position shown in Figure 12 of the drawings, which operation it will be noted, through the associated mechanism, 50 will cause the valve member 24 to shut off communication between the conduit 19 and the conduit 22, and to establish connection between the conduit 22 and the conduit 23, which leads from the source of steam pressure. It will be understood, of course, that 55 the mold sections have been heated to the vulcanizing temperature, and are intended to be constantly maintained at said temperature during the vulcanizing operation upon a single tube, or upon successive tubes, as they are inserted in the mold.

The mold now being in the position shown 60 in Figure 12, and connected with the source of steam pressure, the vulcanizing process is 65 taking place, the length of time for which,

of course, depends upon the nature of the raw rubber compound, of which the tube is composed, and the vulcanizing temperature of the mold, as well as of the heat of the steam or other vulcanizing gas being supplied through the conduit 23.

When the vulcanization process has been completed, the mold assembly is tilted to the position shown in Figure 13, the valve member 15 having been moved to a position to 70 connect the conduit 19 with the vacuum conduit 17, so that when the parts occupy the position shown in Figure 13, the steam and water of condensation within the vulcanized tube will be removed, and said vulcanized 75 tube collapsed within the mold. When this operation has been accomplished, the valve member 15 will be moved to the neutral position shown in Figure 11, whereupon the mold will be moved to the horizontal position, the upper section moved to the position shown in Figure 3, whereupon the vulcanized tube 2 may be removed from the mold, the mold parts being then in position 80 to commence an operation upon another 85 tube.

Summarizing the various steps of my improved method, after the formation of the straight tube 1 as it is delivered from a tubing machine, is (1st) splicing the ends of 90 the tube and inserting the valve stem; (2nd) to collapse the tube and insert it in the mold section 4; (3rd) partially inflate it with cold air or other gas; (4th) after completely enclosing it within the mold, to further inflate it with the cold air or other gas to expand it within the mold; (5th) to reduce the pressure of air or other cold gas to substantially a sub-atmospheric pressure; (6th) project steam or other vulcanizing 100 gas into the tube and maintain the internal pressure of the steam or vulcanizing gas within the tube during the vulcanizing process; and (7th) after the vulcanizing process has been carried on, to remove the steam and water of condensation from the tube by a sucking operation, which last mentioned operation also collapses the tube within the mold, facilitating its ready removal when the mold sections are moved to their open 110 position.

While in the above description I have indicated that I prefer to collapse the tube before inserting it into the lowermost section 4, it will be obvious that this step of the method may be performed after the unvulcanized tube has been inserted into said section; and while I have illustrated certain of the steps of my method as being automatically performed as by means of the tilting of the mold to the position shown in Figure 12, or to the position shown in Figure 13, it will be obvious that both of these operations can be manually performed without departing from the spirit of the invention.

It will accordingly be seen that I have provided a method of producing a pneumatic tube, which is well adapted to attain, among others, all the aims and objects of my invention, in a most efficient manner. The tube produced according to my method is seamless and is of uniform thickness and texture. It is also free from wrinkles upon its inner periphery. Moreover, the forming 10 of the tube of elliptical or oval cross-section, has the advantage that when the tube is inserted within a casing and inflated, the inflating operation will cause the tube to expand equally in all directions, whereby it 15 will be of uniform thickness throughout its whole extent during service.

While I have shown a preferred form of apparatus for carrying out the various steps employed in my method, it is obvious that 20 other forms of apparatus may be employed for carrying out such steps without departing from the scope of the present invention.

It will be noted that the lower mold section is in a horizontal position when the unvulcanized tube is deposited therein. This gives 25 further insurance against the soft rubber compound, of which the tube is composed, softening to such an extent that the upper edge of the tube will fall or lop over the edge 30 of said lower section, so that one or more parts thereof would be pinched between the mold sections when they are closed upon each other.

As many changes could be made in this 35 construction without departing from the scope of the following claims, it is intended that all matter contained in the above description or shown in the accompanying drawings shall be interpreted as illustrative 40 only and not in a limiting sense.

Having thus described my invention what I claim as new and desire to secure by Letters Patent is:—

1. The herein described method of producing a pneumatic tube, which consists in 45 providing a tube of unvulcanized rubber compound, uniting the ends of said tube, withdrawing the air therefrom by suction, filling said tube with steam, and then vulcanizing said tube.

2. The herein described method of producing a pneumatic tube, which consists in providing a tube of unvulcanized rubber, inserting one end of said tube into the other 55 end thereof to form a lapped splice, placing the tube in a closed mold heated to substantially the vulcanizing temperature, withdrawing air from said tube by suction, injecting steam under pressure into said tube, and permitting said heated medium to remain within 60 said tube while it is being subjected to the vulcanizing process.

3. The herein described method of producing a pneumatic tube, which consists in 65 providing a tube of unvulcanized rubber

compound, splicing the ends of said tube, inserting a valve stem therein, placing said tube in a closed mold heated substantially to the vulcanizing temperature, forcing air into said tube through said valve stem to expand 70 the tube within the mold, sucking the air from the tube through said valve stem, and then forcing steam under pressure through said valve stem into said tube, and maintaining the pressure therein while the tube is being subjected to the vulcanizing process. 75

4. The herein described method of producing a pneumatic tube, which consists in providing a tube of unvulcanized rubber compound, splicing the ends of said tube, 80 inserting a valve stem therein, placing said tube in a closed mold heated substantially to the vulcanizing temperature, forcing air into said tube through said valve stem, to expand the tube within the mold, sucking 85 air from the tube through said valve stem, forcing steam, under pressure into said tube, subjecting said tube to the vulcanizing process, and then sucking the steam and water condensation from said tube. 90

5. The herein described method of producing a pneumatic tube, which consists in providing a tube of unvulcanized rubber compound, splicing the ends of said tube, inserting a valve stem therein, placing said tube 95 in a closed mold heated substantially to the vulcanizing temperature, forcing air into said tube through said valve stem, to expand the tube within the mold, relieving the pressure within said tube by removing a 100 quantity of air or other gas therefrom, forcing steam under pressure into said tube, subjecting said tube to the vulcanizing process, and then sucking the steam and water condensation from said tube. 105

6. The herein described method of forming a pneumatic tube, which consists in providing a tube of unvulcanized rubber compound, uniting the ends of said tube, inserting a valve stem therein, placing said tube in one part of a circular mold heated substantially to the vulcanizing temperature, injecting air into said tube, placing the other heated section of the mold upon said first named section, whereby the tube is completely enclosed, injecting a further quantity of air into said tube to expand the same within the mold, sucking the air from said tube, injecting steam under pressure into said tube, permitting said tube with its enclosed steam to remain in said mold while being subjected to the vulcanizing process, then sucking the steam and water of condensation from said tube. 115 120 125

7. The herein described method of forming a pneumatic tube, which consists in providing a tube of unvulcanized rubber compound, uniting the ends of said tube, inserting a valve stem therein, placing said tube in one part of a circular mold heated sub- 130

stantially to the vulcanizing temperature, injecting air into said tube, placing the other heated section of the mold upon said first named section, whereby the tube is completely enclosed, injecting a further quantity of air into said tube to expand the same within the mold, sucking the air from said tube, injecting steam under pressure into said tube, permitting said tube with its enclosed steam to remain in said mold while the tube is being subjected to the vulcanizing process, and then collapsing said tube within said mold by suction, whereby to free it from the mold and remove the steam and water of condensation.

8. The herein described process, which consists in providing a tube of unvulcanized rubber, bringing the ends of said tube together and forming said ends into a lapped union, inserting a valve stem into said tube, placing said tube in one part of an individual sectional mold heated to the vulcanizing temperature, injecting a quantity of relatively cold air into said tube, placing the other part of said section of said heated mold upon the first named section, whereby the tube is entirely enclosed by said mold sections, forcing a further quantity of relatively cold air into said tube to expand the same within the mold, sucking said air from the tube, forcing steam under pressure into said tube while the same is being subjected to the vulcanizing temperature of the mold, sucking the steam and water of condensation from said tube after vulcanization, and then removing said tube from the mold.

9. The herein described method of forming a pneumatic tube, which consists in providing a tube of unvulcanized rubber, uniting the ends of said tube, inserting a valve stem therein, placing said tube in a closed mold heated to vulcanizing temperature, forcing relatively cool air into said tube to expand the same within the mold, sucking said air from the tube, forcing steam under pressure into said tube, allowing said steam under pressure to remain in said tube during the vulcanizing process, sucking said steam and water of condensation from the tube, and then removing the tube from the mold.

10. The herein described process for forming a pneumatic tube, which consists in providing a tube of unvulcanized rubber, placing the ends of said tube in telescoping relation so as to form a lapped splice, inserting a valve stem therein, placing said tube in a closed mold, heated to the vulcanizing temperature withdrawing air from said tube by suction, forcing steam into said tube, and then maintaining a pressure of steam within said tube while the tube is being subjected to the vulcanizing process, whereby the tube is vulcanized and said lapped portions are formed into a homogeneous mass.

11. The herein described method of producing a pneumatic tube, which consists in providing a tube of unvulcanized rubber compound, splicing the ends of said tube, inserting a valve stem therein, placing said tube in a closed mold heated substantially to the vulcanizing temperature, forcing cold air into said tube through said valve stem to expand the tube within the mold, sucking the air from the tube through said valve stem, and then forcing steam under pressure through said valve stem into said tube, and maintaining the pressure therein while the tube is being subjected to the vulcanizing process.

12. The herein described method of forming a pneumatic tube, which consists in providing a tube of unvulcanized rubber compound, uniting the ends of said tube, inserting a valve stem therein, placing said tube in one part of a circular mold heated substantially to the vulcanizing temperature, injecting cold air into said tube, placing the other heated section of the mold upon said first named section, whereby the tube is completely enclosed, injecting a further quantity of cold air into said tube to expand the same within the mold, sucking the air from said tube, injecting steam under pressure into said tube, permitting said tube with its enclosed steam to remain in said mold while being subjected to the vulcanizing process, then sucking the steam and water condensation from said tube.

In testimony whereof, I affix my signature.

WALTER L. FAIRCHILD.
